STOVE

Richard S. Weston, Joliet, Ill., assignor, by mesne assignments, to The Floyd-Wells Company, Royersford, Pa., a corporation of Pennsylvania

Application January 25, 1935, Serial No. 3,431

3 Claims. (Cl. 126—36)

This invention relates to stoves and more particularly to two-fuel oven combustion stoves.

A principal object of the invention is the provision of means for simultaneously opening a normally closed secondary air inlet to and flue outlet from the oven of such a stove when gas is used as a fuel for heating the oven.

Another important object of the invention is the provision of operating means for such opening means, which will simultaneously control the fuel supply to the oven burner or the broiler burner of the oven.

Numerous other objects and advantages of the invention will be apparent as it is better understood from the following description, which, taken in connection with the accompanying drawing, discloses a preferred embodiment thereof.

In the drawing,

Figure 1 is a rear elevation of a stove embodying the invention, with part of the clean-out plate broken away to show the flue outlet closing means;

Fig. 2 is a partial horizontal sectional view taken substantially on the line 2—2 of Fig. 1; and

Fig. 3 is a detail horizontal section taken substantially on the line 3—3 of Fig. 1.

Referring more particularly to the drawing, a stove of any desired construction is indicated generally by reference numeral 11, and comprises a two-fuel oven 12 of known construction having a door 13 at the front, side walls 14, a rear wall 15, which extends laterally to form the rear wall for the whole stove, a broiler burner 16 adjacent the top, and an oven burner 17 in the bottom thereof.

Fuel is supplied to the broiler burner 16 and oven burner 17 by pipes 18 and 19, respectively, which are controlled by a two-way valve mechanism 21, of any desired construction, connected to a main supply pipe 22. The valve 21 is controlled by a rod 23 suitably mounted for rotation in the frame or walls of the stove 11 and having an operating handle 24 secured to its forward end, whereby the direction of rotation of handle 24 will determine whether fuel will be supplied to oven burner 17 or broiler burner 16.

Rigidly secured to the rod 23 adjacent the valve 21 is one end of a lever 25, the other end of which is pivotally secured to the upper end of a depending lever 26, the lower end of which is pivotally connected at 27 to a horizontal extension or lug 28 on a plate member 29. The plate member 29 has a vertical slot 31 therein which engages and co-operates with a pair of

bolts or lugs 32 secured in any suitable manner to the rear wall 15 of the stove 11.

Rigidly secured in any desired manner to the rear wall 15 is a U-shaped member 33 which, with said wall, constitutes the lower portion of 5 the usual flue that leads to a stack (not shown), and has a clean-out aperture 34 conveniently located therein and normally closed by a plate 35.

Adjacent the plate 29, the member 33 is or may be provided with a laterally extending lug 36 10 adapted to assist in maintaining the plate 29 against the rear wall 15 and, together with the slot 31 and pins 32, in guiding it in its vertical movement, the function of which will be later described.

An aperture 37 is provided in the upper part of the rear wall 15 which constitutes a flue outlet or opening from the oven 12 to the flue defined by the wall 15 and the member 33. The flue outlet 37 is normally closed by a plate or member 38. An extension 39 of the plate 38 extends to the right, viewing the drawing, through the left-hand end wall of the member 33, which point constitutes an effective pivot for the member 38. The protruding end of the extension 39 co-operates with a suitable hole in the upper end of a vertical extension 41 of the plate 29 so that when the plate 29 is in its lower or normal position, as illustrated, it will maintain the plate 38 in a substantially horizontal position to keep the flue outlet 37 closed, and when plate 29 is raised, plate 38 will drop or be forced clockwise about its pivot point to open the flue outlet 37. In its lower position the plate 29 is also adapted to cover an aperture 42 in the rear wall 15 which constitutes a secondary air inlet 25 to the oven 12 which will be opened when the plate 29 is raised.

When neither the oven gas burner 17 nor the broiler burner 16 is in use, the secondary air inlet 42 and the flue outlet 37 are closed. In order to use either the burner 16 or the burner 17, handle 24 is rotated in one direction or the other, respectively, thus actuating the two-way valve 21 in known manner. Simultaneously with any 45 actuation in either direction of handle 24, rod 23 actuates levers 25 and 26 to raise plate 29 to open the secondary air inlet 42 and the flue outlet 37.

It is thought that the invention and many of 50 its attendant advantages will be understood from the foregoing description, and it will be apparent that various changes may be made in the form, construction and arrangement of the parts without departing from the spirit and scope of the 55

invention or sacrificing all of its material advantages, the form hereinbefore described being merely a preferred embodiment thereof.

I claim:

- 5 1. In a stove having an oven, an oven burner, a broiler burner in said oven, a secondary air inlet to said oven, a member normally closing said secondary air inlet, a flue outlet from said oven, and a second member normally closing said flue outlet; a valve member operable in one direction to control the fuel supply to said oven burner and operable in the other direction to control the fuel supply to said broiler burner, and connecting devices between said valve member and said first 10 member and between said first member and said second member for operating said first and second members simultaneously to open said secondary air inlet and said flue outlet when said valve member is operated in one direction or the other to supply fuel to said oven burner or said broiler burner.
- 15 2. In a stove having an oven, an oven burner in the lower part of said oven, a broiler burner in the top of said oven, a vent for said oven, a damper normally closing said vent, a fuel supply 20

for said burners, a valve controlling said fuel supply operable when turned in one direction to supply fuel to the oven burner and operable when turned in the opposite direction to supply fuel to the broiler burner, means connecting said damper to said valve whereby said damper is moved to open position when said valve is turned to supply fuel to either of said burners. 5

3. In a stove having an oven, an oven burner, a broiler burner in said oven, an aperture in a wall of said oven, a member normally closing said aperture, a flue outlet from said oven, and a second member normally closing said flue outlet; a valve member operable in one direction to control the fuel supply to said oven burner and operable in the other direction to control the fuel supply to said broiler burner, and a connecting device between said valve member and said first member and between said first member and said second member for operating said first and second members simultaneously to open said aperture and said flue outlet when said valve member is operated in one direction or the other to supply fuel to said oven burner or said broiler burner. 10 15 20
